UNITED STATES PATENT OFFICE.

ABRAHAM POSNER, OF BROOKLYN, NEW YORK.

FASHIONED ANKLE AND ARCH SUPPORT.

Application filed August 19, 1921. Serial No. 493,559.

To all whom it may concern:

Be it known that I, ABRAHAM POSNER, a citizen of the United States, and a resident of the city of New York, borough of Brooklyn, in the county of Kings and State of New York, have invented a new and Improved Fashioned Ankle and Arch Support, of which the following is a full, clear, and exact description.

10 The invention relates to boots and shoes, and its object is to provide a new and improved fashioned ankle and arch support, more specially designed for insertion in boots or shoes of standard makes and sizes 15 and fashioned according to the human foot to provide an aid for the same, particularly when the wearer is exercising, walking, climbing, golfing, skating, or indulging in other sports liable to strain the foot.

20 Another object is to provide a special support for the ankle bone.

Another object is to sustain the arch of the foot.

Another object is to permit of fashioning 25 and applying the ankle and arch support to deformed feet.

With these and other objects in view the invention consists of certain novel features of construction as hereinafter shown and 30 described and then specifically pointed out in the claims.

A practical embodiment of the invention is represented in the accompanying drawings forming a part of this specification, in 35 which similar characters of reference indicate corresponding parts in all the views.

Figure 1 is a plan view of the blank from which the improved ankle and arch support is made.

40 Figure 2 is a side elevation of the improved ankle and arch support in position in a shoe, the latter being shown in section.

Figure 3 is a rear end elevation of the improved ankle and arch support in position 45 on a foot.

Figure 4 is a side elevation of the same.

Figure 5 is a cross-section of the same on the line 5—5 of Figure 4.

The improved ankle and arch support is 50 made from a single piece of leather, sheet metal, or other suitable sheet material and is fashioned according to a normal foot over a suitable last thereof, but if desired, the ankle and arch support may be fashioned over a corresponding last for a deformed foot. Mainly, however, the ankle and arch sup-

port is to be fashioned over standard lasts of all makes and sizes to permit of readily inserting the ankle and arch support in standard boots and shoes. The ankle and arch support comprises a base 10, sides 11 and 12, and a back 13 integrally connecting the sides 11 and 12 with each other at their lower portions, so as to leave the upper portions of the sides free and unattached to 60 permit freedom of the foot when exercising. The side 11 rises integrally from the arch side of the base 10 and the lower end of the other side 12 is provided with an inwardly extending flange 14 overlying and fastened to the base 10 and the back 13 is provided with a flange 15 forming a continuation of the flange 14 and likewise overlying and being secured to the base 10 at the rear thereof. The fastening means employed for fastening the flanges 14 and 15 to the base 10 may be rivets, or similar fastening devices, or the flanges may be fastened by glue, cement, or other adhesive substances to the base 10. 70

The sides 11 and 12 are provided with depressions 20 and 21 for accommodating the ankle bone of the foot. The arch 22 of the base 10 is preferably reinforced either by thickening the material at this portion 80 or by attaching a separate reinforcing piece to the arch. It is understood that in case the improved ankle and arch support is made of leather, it will be necessary to reinforce the arch by a separate piece, but in case the ankle and arch support is made of metal, the latter may be thickened correspondingly at the arch. 90

In the manufacture of the ankle and arch support, the sheet material is cut out to 95 form a blank as shown in Figure 1, and in case the blank is made of leather or a similar material, then it is dampened and pressed by suitable dies onto a standard last of a corresponding size to fashion the ankle and arch support according to a normal foot. In case the blank is made of metal, it is pressed in a machine on a standard die to give it the correct shape according to a normal foot. After the stamping or fashioning operation is completed, the flanges 14 and 15 are fastened to the base 10 as previously explained and the now finished ankle and arch support is ready for insertion in a standard boot or shoe of a corresponding size. Although the ankle and arch support is mainly intended for use in boots 100 105 110

and shoes of standard makes, it is evident that the ankle and arch support may be fashioned over a last for a deformed foot.

Having thus described my invention, what 5 I claim as new and desire to secure by Letters Patent is:

1. As an article of manufacture an ankle and arch support fashioned from a single piece of material and comprising a base 10 adapted to rest on the sole of a boot or shoe, a back, and sides integrally connected with each other by the said back one side extending integrally from one side of the base the entire length thereof, the lower 15 front portion of said side gradually decreasing in height, the other side terminating approximately at the center of length of the base and it and the said back being provided at their lower ends with an inwardly extending flange secured to the said base.

2. As an article of manufacture an ankle and arch support fashioned from a single piece of material and comprising a base 25 adapted to rest on the sole of a boot or shoe, a back, and sides integrally connected with each other by the said back and discon-

nected with each at their rear upper portions, one side extending integrally from one side of the base the entire length thereof, 30 the lower front portion of said side gradually decreasing in height, the other side terminating approximately at the center of length of the base and the said back being provided at their lower ends with a continuous inwardly extending flange overlying the said base, and fastening means fastening the flange to the base.

3. As an article of manufacture, an ankle and arch support formed from a single piece of material and comprising a base 40 having its arch portion thickened, a back and sides integrally connected with each other by the back and having their rear upper portions disconnected, one side extending integrally from one side of the base the entire length thereof, the lower 45 front portion of said side gradually decreasing in height, the other side terminating approximately at the center of length of the base and it and the back provided at their lower ends with inwardly extending flanges secured to the base.

ABRAHAM POSNER.
